RAY L. CARTER, OF SYRACUSE, NEW YORK, ASSIGNOR OF ONE-HALF TO LOUIS O. BUCHHOLZ, OF SYRACUSE, NEW YORK.

DISK GRINDER.

1,244,584.

Specification of Letters Patent. Patented Oct. 30, 1917.

Application filed August 21, 1916. Serial No. 115,936.

To all whom it may concern:

Be it known that I, RAY L. CARTER, a citizen of the United States, residing at Syracuse, in the county of Onondaga and State of New York, have invented certain new and useful Improvements in Disk Grinders, of which the following is a specification.

This invention relates to improvements in disk grinders, and has for its object to provide a novel, simple and compact machine of the class, designed particularly for use by pattern-makers, wood and metal polishers, and the like, wherein the abrading disk is driven by direct connection with a motor or other source of power. A further object is to provide a grinder of the class wherein the revolving disk-support comprises a fan for blowing away the dust which results from the grinding. And a further object is to provide novel and simple means for tilting the work-table to different angles relatively to the plane of the grinding disk, the same means being employed for imparting vertical movements of the work-table.

I attain these objects by the means set forth in the detailed description which follows, and as illustrated in the accompanying drawings, in which—

Figure 1 is a front side elevation of the complete device. Fig. 2 is a right side elevation; showing by full and dotted lines the various positions of the work-table, and the means for operating the same. Fig. 3 is a central vertical cross-section, taken on line 3—3 of Fig. 1; showing the construction and arrangement of the grinding disk and blower. Fig. 4 is a rear side elevation; showing the common means for tilting, as well as for raising and lowering, the work-table. And Fig. 5 is a sectional view taken on line 5—5 of Fig. 2.

In the drawing, 2 represents a base or standard which supports the working and other parts of the grinder, upon the top of which is mounted an electric motor 3 which drives the grinding disk and fan, the said motor having a base 4' which dove-tails into the grooved top of the base 2. 4 represents the armature shaft of the motor, and 5—5' represent wires connecting the motor with a source of electricity.

6 represents the grinding or abrading disk, which is preferably a circular sheet of heavy sand-paper for grinding wood, or it

may be emery or other abrasive material for grinding metal. The disk 6 is securely mounted upon one face of a metal disk 7, having a central hub 7', the latter bored out to receive one end of the armature shaft, 60 and held in place by a set-screw 8. The periphery of disk 7 is chamfered at its rear edge and the reduced portion thereof is inserted in a circular opening 9' of a hollow substantially circular casing 9, which is disposed concentric to and is pierced by the shaft 4. The casing 9 may be rigidly held in place by any suitable means, as a bracket 10 and screws 10', by which it is anchored to the base 2. The rear side of the casing 9 has an outwardly projecting hollow boss 11, which extends from a short distance above the center to the bottom of the casing, for providing a hollow space 11'. The space 11' extends below the casing 9 and in the front face of the said casing is a slot 13. 14 represents a dust guard which is disposed over the lower half of the disk 6, being secured to the casing 9 by screws 14'. The top edge of the guard is positioned slightly below the center and is spaced slightly from the disk 6. The lower edge of the guard overlaps the slot 13. The object of the guard 14 is to receive the dust resulting from the grinding as it is carried downwardly by 85 the rotation of disk 6. The rear face of the rotary support 7 is provided with a number of integral fan leaves 16, preferably spaced radially near the peripheral edge of the support. During the rotation of disks 6 and 7 90 the leaves 16 suck the dust into the hollow space between the guard 14 and the disk 6, thence through the slot 13 into the hollow space 11', thence upwardly in the boss 11 to the center of the casing 9 and through 95 a circular opening 17 in the rear wall of the casing, concentric to an internal hub 12 of the casing, thence upwardly again and is discharged through nozzle 18 (see arrows in Figs. 1, 2, 3, and 4). A hose or other conductor (not shown) may be attached to the nozzle 18 for carrying the dust to a convenient point.

The work or object to be ground by the disk 6 is placed on top of a table 19 which is normally positioned horizontally so that its top side is about on a level with the center of shaft 4, and disk 6, as shown by the full lines in Figs. 1, 2, 3, and 4. The table 19 is supported by an arc-shaped 110

bracket 20 which is rigidly connected to one end of the table by a screw 20'. The bracket 20 has a slot 21 and a tongue 21', the latter fitting and sliding in a groove 22' of a similar stationary arc-shaped guide 22, which is slidable on a square guide 23, by means of a sliding part 23'. The lower end of the guide 23 is embedded in a boss 23'' at the bottom of the base 2. The top of the guide 23 is held steady and truly vertical by a cap 24 and a bracket 24' which is secured to the base 2 by bolts 25. The table 19 is positioned relatively to the disk 6 so that it may be tilted on a circle the center 15 of which is substantially the point 19' of said table. The bracket 20 has an arc-shaped rack 26 on its underside which is engaged and driven by a pinion 27, the latter being mounted upon the shaft 28, and 20 the latter being journaled in a lug 29 of the slide 23'. The shaft 28 is manipulated by a hand-wheel 28'. The gear 27 is preferably made rigid on the shaft 28 by the pin 27'. 30 represents a second rack which is 25 rigid on the guide 23 and this rack is engaged by a pinion or gear 31, the latter being normally loose on the said shaft, when the shaft and gear 27 are in the position shown in full lines in Fig. 4. The opposite 30 end of the shaft 28 is provided with a flange 32, and a spring 33 is interposed between said flange and gear 31 for normally holding said gear in the idle position and against the lug 29. When it is desired to tilt the 35 work-table 19 from the horizontal position to any angle, as indicated by the dotted lines in Fig. 2, the operator turns the hand-wheel 28' in the proper direction. The pinion 27 which is held in engagement with the rack 26 by spring 33, operates the said rack and the bracket 20, the latter will then slide on the guide 22 and tilt the table. When, however, it is desired to lower the table 19, as to the position shown by dotted lines in 40 Fig. 2, the operator pulls outwardly on the shaft 28, which action disconnects the gear 27 from the rack 26 (see dotted lines Fig. 4), and brings a pin 34 carried by the other end of said shaft into engagement with the 45 notch 35 in the hub of gear 31. The latter gear will then rotate with the said shaft and being in engagement with the rack 30 it carries the table downwardly, as described. 36 represents a number of clamping 50 screws which are threaded into the guide 22 and are provided with heads 36' which engage the bracket 20, (see Figs. 2 and 5) for holding the table 19 in the different positions relatively to the center 19'. 55 The free end of the bracket 20 is cut away at 37 for indicating and reading graduations 38 on the corresponding end of the guide 22, the said graduations being employed by the operator for setting the table 60 19 at the desired angle relatively to the disk 65

6. 39 represents set screws carried by the slide 23' for securing said part in any desired position on the guide 23.

My disk grinder is extremely simple and compact and can be produced at a relatively small cost. The provision of the blower 7-16 within the casing 9 which partially receives and is arranged concentric to the grinding disk support, is a novel and economical construction and arrangement which 75 enables me to eliminate several extra parts and also an extra drive for the blower, as compared with the older styles of grinders of the class. Furthermore, the provision of the two racks 26 and 30 and the pinions 27 and 31, the latter being operated by a single shaft, is also a novel improvement which saves a number of parts as well as considerable time in the operation of the adjustable work-table.

Having thus described my invention, what I claim as new and desire to secure by Letters Patent, is—

1. The combination with a support, of a grinding wheel carried thereby, a guard covering a portion of the surface of the wheel and having a suction mouth, an adjustable work-table extending across said wheel and having its inner end arranged at approximately the mouth of the guard, and near the surface of the grinding wheel, the inner end of the table and the mouth of the guard being formed to permit a substantial adjustment of the table in a circle independently of the guard, yet maintaining the inner end thereof in close proximity to the mouth of the guard, and suction creating means for collecting the dust entering the guard, and resulting from the grinding, substantially as described.

2. The combination with a support, of a grinding wheel carried thereby, a fan, a casing surrounding the fan, a guard extending across the surface of the grinding wheel, and having an inlet mouth, a work table disposed, across the grinding wheel and having its inner end terminating at approximately the mouth of the guard, the inner end of the table and the mouth of the guard being beveled to permit an angular adjustment of the table relative to the grinding wheel, yet maintaining the end thereof adjacent of the mouth of the guard, and means for rotating the fan for creating an air current to discharge the dust entering the guard and resulting from the grinding of the work supported on the table.

3. The combination with a support, of a grinding element carried thereby having a broad grinding face, a guard extending across said face, and covering the lower portion thereof and having an inlet mouth terminating in close proximity to the surface of the grinding element, a work table disposed parallel with the guard and having

its inner edge arranged adjacent the mouth of the guard, means for rotating the grinding element and suction creating means for collecting dust resulting from the grinding 5 operation.

4. The combination with a support, of a grinding wheel having a broad grinding face, a guard extending across said face and covering the lower portion thereof and having an inlet mouth, a work table disposed 10 parallel with the guard having its inner

edge terminating in close proximity to the mouth of the guard, the inner edge of the work table and the upper edge of the guard being fashioned to permit a swinging movement of the table relative to the guard, yet maintaining the same in close relation thereto, and means for rotating the grinding wheel. 15

In testimony whereof I affix my signature.

RAY L. CARTER.
